CLIP FOR A DRAPERY PLEATER

Ben Walters, Bronx, N. Y.

Application February 8, 1949, Serial No. 753

Term of patent 3½ years

(Cl. D17—3)

To all whom it may concern:

Be it known that I, Ben Walters, a citizen of United States of America, residing at Bronx, New York, in the county of Bronx and State of New York, have invented a new, original, and ornamental Design for a Clip for a Drapery Pleater, of which the following is a specification, reference being had to the accompanying drawing, forming part thereof.

In the drawing

Fig. 1 is a top plan view of a clip for a drapery pleater, showing my new design;

Fig. 2 is a front elevational view;

Fig. 3 is a side elevational view; and

Fig. 4 is a rear elevational view.

I claim:

The ornamental design for a clip for a drapery pleater, as shown.

BEN WALTERS.
